UNITED STATES PATENT OFFICE.

WILLIAM M. LEVY, OF ST. LOUIS, MISSOURI, ASSIGNOR OF TWO-THIRDS TO
ADOLPH BERND AND ROTHSCHILD BROTHERS, ALL OF SAME PLACE.

HOLDER AND PACKING-FRAME FOR HATS.

SPECIFICATION forming part of Letters Patent No. 404,636, dated June 4, 1889.

Application filed March 5, 1889. Serial No. 301,965. (No model.)

To all whom it may concern:

Be it known that I, WILLIAM M. LEVY, a citizen of the United States, residing at the city of St. Louis, State of Missouri, have invented a certain new and useful Improved Holder and Packing-Frame for Hats, of which the following is a full, clear, and exact description.

My invention relates to improved means of holding and packing hats, and has for its object to facilitate the exhibition thereof and to enable a number of hats to be packed together and carried without injury.

It consists in an extensible and retractible frame having transverse bars or holders, combined with features of novelty, as hereinafter claimed.

On the accompanying drawings, Figure 1 represents a side elevation of my improved 20 hat-holder and packing-frame in its closed position and containing a number of hats packed together for carriage; Fig. 2, a similar view thereof, broken away, when opened out for the exhibition or removal of the hats; Figs. 25 3 and 4, a plan and front elevation, respectively, of the device as seen in Fig. 1; and Figs. 5 and 6, corresponding views to Figs. 1 and 2, respectively, broken away, showing a modified arrangement of locking device, like 30 letters of reference denoting like parts in all the figures.

a a represent two sides or frames, which are mounted opposite and parallel to each other at a suitable distance apart. Each side 35 frame *a* is composed of bars arranged together in consecutive pairs, the bars of each pair crossing one another diagonally at the center, where they are swiveled together and jointed near their respective ends, at an equal distance 40 on each side of the central joint, to the corresponding ends of the succeeding pair, and so on through the entire series on the well-known "lazy-tong" principle.

The end joints of the bars of one side frame 45 *a* are respectively connected to or formed in one with the corresponding joints of the opposite side frame *a* by transverse bars or holders *b b' b² b³ b⁴ b⁵ b⁶*, the whole constituting an extensible and retractible frame for 50 receiving the hats 1 2 3 4 5 6, which, when the frame *a b b'*, &c., is in an upright position and extended or opened out, as seen in Fig. 2,

are placed centrally between the side frames *a*, so that the front and rear portions of the rim of hat 1 rest upon and are supported by 55 the horizontally-opposite bars or holders *b'*, respectively, hat 2 by the bars or holders *b²*, and so on throughout the entire series of hats and holders, in which positions the hats are conveniently arranged for exhibition or for 60 removal, as indicated by dotted lines for hat 1.

On retracting or closing the frame *a b b'*, &c., into the position seen in Fig. 1, the crown of the lowest hat 6 enters the crown of hat 5, the crown of hat 5 that of hat 4, and so on 65 throughout the series, whereby the hats 1 to 6 are packed together in the smallest possible space within the frame *a b b'*, and the whole can be stowed in any position within a traveling-trunk or otherwise for carriage. 70

To prevent the frame *a b b'*, &c., from being closed too far and so injuring the hats, I couple together any two opposite end joints (one on each side of the central joints) of the lazy-tong bars composing each side frame *a* 75 by two arms or links *c*, which are jointed at one end to the corresponding end joints of the lazy-tong bars, and at their other ends to each other by a pin *c'* at half the distance between the said joints of the lazy-tong bars 80 when the latter are closed to the full permitted extent, so that on closing the frame *a b b'*, &c., the arms *c* will be brought from their position seen in Fig. 2 into line and direct tension with each other, as seen in Fig. 1, thereby locking the end joints of the lazy-tong bars 85 and preventing any further lowering or closing of the frame *a b b'*, &c. As the frame *a b b'*, &c., is opened out or extended, the arms or links *c* will be converged about their common joint *c'* and resume the position seen in 90 Fig. 2.

For locking the frame *a b b'*, &c., in the open or extended position, any two consecutive central joints of the lazy-tong bars are 95 coupled together by arms or links *d*, which are jointed to each other by a pin *d'* at half the distance between the said central joints when the lazy-tong bars are fully extended, in which position of the latter the arms *d* are 100 in vertical line with each other and act as a strut to prevent the closing of the frame *a b b'*, &c.; or, in lieu of the separate arms *c* and *d* for locking the frame *a b b'*, &c., in the

- closed and open positions, respectively, as above described, I may substitute for the two arms *c* a single bar *e*, as shown in Figs. 5 and 6, which is formed near one end with a longitudinal slot *e'*, of suitable extent, along the bar *e*, which is jointed to the coupling-pin *d'* of the arms *d*, connecting the consecutive central joints of the lazy-tong bars, the slot *e'* working over the adjacent end joint of the lazy-tong bars, so that when the latter are fully closed, as seen in Fig. 5, the outer end of the slot *e'* is drawn hard against and behind the said end joint, which is thereby prevented from further spreading and the frame *a b b'*, &c., locked in the closed position.
- On extending or opening the frame *a b b'*, &c., into the position seen in Fig. 6, the said end joint of the lazy-tong bars has free play within the slot *e'* of the bar *e* until, on the arrival of the arms *d* in line with each other, a notch *h*, formed in the upper side of the slot *e'*, comes opposite to the said joint, and is engaged therewith for locking the arms *d* in the extended position of the frame *a b b'*, &c.
- ff* represent bands of elastic webbing or other material (see Fig. 4) arranged along the upper surface of the bars or holders *b' b' b'*, to which their ends are attached by links *g* or otherwise, so that when hats 1 2 3 are located within the frame *a b b' b'* the bands *f*

are hitched over the front and rear portions of the respective rims of the hats 1 2 3, which are thereby secured to the bars or holders *b' b' b'*.

I claim as my invention—

35

1. In a holder and packing device for hats, the combination of sides or frames, each composed of bars jointed together on the lazy-tong principle, and bars or holders connecting the said frames, with means for locking the frames in the extended and closed positions, substantially as shown, and for the purpose described.

40

2. In a holder and packing device for hats, the combination of sides or frames, each composed of bars jointed together on the lazy-tong principle, bars or holders connecting the said frames, and means for locking the frames in the extended and closed positions, with means for securing the hats to the said connecting bars or holders, substantially as shown, and for the purpose described.

45

50 In testimony whereof I affix my signature, in presence of two witnesses, this 28th day of February, 1889.

WILLIAM M. LEVY.
